No. 640,450.

Patented Jan. 2, 1900.

J. P. CRONIN.

ATTACHMENT FOR WINDING MACHINES.

(No Model.)

(Application filed Sept. 8, 1899.)

UNITED STATES PATENT OFFICE.

JOHN P. CRONIN, OF PATERSON, NEW JERSEY.

ATTACHMENT FOR WINDING-MACHINES.

SPECIFICATION forming part of Letters Patent No. 640,450, dated January 2, 1900.

Application filed September 8, 1899. Serial No. 729,825. (No model.)

To all whom it may concern:

Be it known that I, JOHN P. CRONIN, a citizen of the United States, residing in Paterson, county of Passaic, and State of New Jersey, have invented an Attachment for Winding-Machines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention has reference to machines for winding silk or other filaments from swifts onto bobbins. In machines of this nature at present in use no means is provided for determining or measuring the amount of material that is wound onto the bobbins, and since the attendant has to depend alone upon the comparative appearance of the bobbins when wound in order to determine whether they contain even approximately the quantity of material intended some bobbins are often wound with considerably more and some with considerably less than that quantity.

The object of this my present invention, therefore, is to provide a simple and efficient means for measuring the material as fast as it is fed onto the bobbins.

A further object of the invention is to provide means for automatically stopping the feed of the material onto each bobbin at such times when the winding of the quantity predetermined has been completed.

The invention consists in an attachment for winding-machines whereby the quantity of material wound upon the bobbin from the swifts may be measured and in the combination and arrangement of the various parts thereof, substantially as will be hereinafter pointed out, and finally embodied in the clauses of the claim.

The invention is fully illustrated in the accompanying drawings, wherein—

Figure 1 is a sectional view of a portion of a winding-machine provided with my improvement, enough of said machine being shown to illustrate the invention. Fig. 2 is a view in front elevation of what is shown in Fig. 1. Fig. 3 is a view in front elevation of one of a pair of swift-hangers, showing my

measuring attachment mounted thereon. Fig. 4 is a sectional view, slightly enlarged, through a certain indicator-block and showing in elevation a revoluble feed-screw connected therewith. Figs. 5 and 6 are enlarged transverse sectional views on the lines xx and yy , respectively, in Fig. 3; and Fig. 7 is an enlarged view in elevation of a modified form of indicator-block, showing in section a revoluble feed-screw which actuates it.

In said drawings, a designates the upper central rail of a winding-machine, and b designates one of a pair of other rails or beams that are disposed at both sides of the rail a and extend, like said rail a , throughout the length of the machine.

c designates one of two or more bearing-brackets in which is journaled the drive-shaft d , carrying friction-wheels e and operated from a suitably-driven shaft f through bevel-gearing g .

h denotes other brackets that are secured to the rail b and project therefrom over the brackets c , having notches i , that provide bearings for the trunnion of the bobbins j and adapted to support the reciprocating rod k , upon which are mounted the thread-guides l .

m indicates the swift-hangers. Each of said swift-hangers consists, as usual, of a bar n , having integrally formed therewith at one of its ends an attaching-plate o and at the other of its ends a hook-shaped bearing-socket p , wherein is adapted to rest one of the trunnions q of a swift r . The bar projects at an incline from the attaching-plate and is secured thereby to the rail a in such a manner as to bring its bearing-socket approximately beneath the bobbins and the neighboring parts in the usual manner.

My attachment may be described as follows: s indicates an elongated metallic casing which is substantially semicylindrical in shape in cross-section and which is provided with integral oppositely-disposed attaching fingers or lugs t , preferably at each of its ends. The casing also has preferably integral end walls u , and it is adapted to be secured to the bar n with the edges of said end walls in contact with one of the faces of said bar, the fingers t being forced around the edges of the bar and clamped against its other face. In the walls u of the casing is journaled a feed-

screw v , said feed-screw having a collar w and a nut z for maintaining it in its bearings in the casing. The lower end of this feed-screw projects beneath the lower end wall of 5 the casing, and it carries a star-wheel a' , that is adapted to be engaged by a tappet or finger b' , that is attached onto one of the spokes of the swift. Thus each time the swift revolves 10 said tappet engages one of the points of the star-wheel, so as to impart a partial revolution to the feed-screw. The casing is provided with a longitudinal slot c' , and adjacent said slot its outer face is marked off in 15 a series of graduations e' , which may be numbered consecutively or otherwise indexed, as required, preferably beginning at the bottom of the casing.

e' designates the indicator-block. Said block consists of a sleeve member f' , which 20 incloses a shoe g' , in which shoe is swiveled the inner end of a spindle h' , that is screwed into and projects through the sleeve and has its outer end bent off at an angle and formed 25 into a knob i' . The sleeve is penetrated by 25 the feed-screw v , and it should be remarked that the face of the shoe which is adjacent to the feed-screw and also the opposing portion of the interior surface of the sleeve are threaded, so as to engage the threads of said feed- 30 screw. Thus when the spindle h is manipulated in an obvious manner, so as to bring its threaded surface and the threaded portion of the interior surface of the sleeve in engagement with the threads of the feed-screw, an 35 operative engagement between the indicator-block and the feed-screw will be effected, whereupon when the latter is rotated the former will move longitudinally thereon.

The lower end of the slot c' is provided with 40 a communicating notch or recess j' , formed in the casing. The friction between the indicator-block and the feed-screw will tend to 45 maintain the spindle h' against one side or edge of the slot c' , and it is on this side of the slot that the recess j' should be formed, for a reason hereinafter more particularly explained.

In Fig. 7 I have shown a modified form of 50 the indicator-block, which consists of a clip k' , that is shaped to partially surround the feed-screw, and a lever l' , which is fulcrumed on a spindle m' (corresponding to the spindle h') and is provided with a shoe n' (corresponding to the shoe g') at one of its ends and is 55 actuated by a spring o' at the other of its ends to maintain the shoe in contact with the feed-screw. It should be remarked that portions of the surface of both the clip and the shoe which contact with the screw should be threaded 60 to engage the latter the same as in the case of the indicator-block first described.

In operation, one of my attachments being secured to each of the swift-hangers, as hereinbefore sufficiently described, and the indicator-block being set at that mark on the graduated scale d' which indicates the number of yards of material which the respective

bobbin is to contain, as the revolving bobbin draws upon the swift through the medium of the thread which is being wound from one 70 onto the other the swift will be rotated, its tappet b striking against the points of the star-wheel, and thus rotating the feed-screw. As the feed-screw rotates the indicator-block 75 will move downwardly toward the lower end of the casing. When it has moved far enough so that its spindle is opposite the recess j' , (the friction between the block and the feed-screw tending to force the spindle in the direction of the recess,) said spindle will enter 80 the same. Thereupon its knob will be projected into the path of one of the spokes of the swift, the impact of which will thus stop the rotation of the swift, and consequently the feed of the material will be automatically 85 cut off at that point where the desired quantity has been wound upon the bobbin. It is of course necessary that the spindle project far enough so as to efficiently engage one of the spokes of the swift at the proper time. 90

It will be apparent that although I have hereinbefore described my attachment with reference particularly to its adaptability for use in connection with a winding-machine the device is also applicable to other machines 95 where it is necessary or desirable to measure the material being placed on bobbins, rollers, or in any other manner wound.

Having thus fully described my invention, what I claim as new, and desire to secure by 100 Letters Patent, is—

1. In a thread-winding machine, the combination of a suitably-sustained swift-hanger, a swift carried thereby, a measuring instrument or indicator adapted to be operated by 105 the swift, and a knob or finger actuated by the measuring instrument and to be thereby projected into the path of the swift to stop rotation thereof.

2. In a winding-machine, the combination 110 of a swift or reel, arms for supporting said swift or reel and on which it may rotate, of a measuring device or indicator comprising a casing or frame provided with a scale and secured to one of said arms, a feed-screw supported in said casing, an indicator-block engaging said screw, and movable thereon, a star-wheel mounted on said screw, and means connected to the swift or reel for engaging said star-wheel as the former revolves. 115

3. In a winding-machine a measuring device or indicator consisting of a suitably-elongated casing or frame having a longitudinal slot therein provided with a recess and a scale adjacent said slot, a feed-screw journaled in 120 said casing parallel with the slot, an indicator-block adjustably engaging the feed-screw and movable relatively to the scale, said block comprising a sleeve member, a shoe inclosed thereby and a spindle projecting through the slot, and a star-wheel mounted on said feed-screw, substantially as described. 125

4. In a winding-machine, the combination, with a suitably-sustained swift-hanger, a

swift journaled in said hanger, an elongated casing or frame secured to said hanger and provided with a longitudinal slot and a scale adjacent said slot, a feed-screw journaled in said casing parallel to the slot, an indicator-block adjustably engaging the feed-screw and movable relatively to said scale, said block comprising a spindle projecting through the slot, a star-wheel mounted on said feed-screw, and a tappet carried by the swift and adapted to engage said star-wheel, said casing being provided with a recess adjacent the swift and communicating with the slot, substantially as described.

15 5. In a winding-machine, the combination with a suitably-supported swift, a measuring device or indicator comprising a slotted casing having a recess at or near one end thereof, a block movable lengthwise of the casing

and carrying a spindle, and means actuated by the swift for moving said block and turning the spindle into the said slot.

6. In a measuring device, the combination of a casing or frame provided with a slot and scale, a screw contained within said casing, 25 a block on said screw and carrying a spindle, a notch or recess formed in said casing and communicating with said slot, the said spindle being adapted to be forced into said recess by the turning of said screw.

In testimony that I claim the foregoing I have hereunto set my hand this 29th day of August, 1899.

J. P. CRONIN.
